UNITED STATES PATENT OFFICE.

CHARLES F. HRADECKY, OF FLEMING, COLORADO.

FREIGHT-CAR SEAL.

1,151,183.

Specification of Letters Patent. Patented Aug. 24, 1915.

Application filed September 9, 1914. Serial No. 860,872.

To all whom it may concern:

Be it known that I, CHARLES F. HRADECKY, a citizen of the United States, residing at Fleming, in the county of Logan, State of Colorado, have invented certain new and useful Improvements in Freight-Car Seals; and I do hereby declare the following to be a full, clear, and exact description of the invention, such as will enable others skilled in the art to which it appertains to make and use the same.

This invention relates to improvements in freight car door seals and more particularly to that type of seal known as "self locking."

An object of the invention resides in the provision of a car seal of the above character which is strong and durable in construction, reliable and efficient in use, and which comprises a minimum number of parts whereby the cost of production will be reduced to the minimum.

With the above and other objects of similar nature in view, the invention consists in the construction, combination and arrangement of parts set forth in and falling within the scope of the appended claim.

In the drawings, Figure 1 is a perspective view of a car seal constructed in accordance with the invention, Fig. 2 is a sectional view taken longitudinally through the device, Fig. 3 is a similar view taken at right angles to Fig. 2, and Fig. 4 is a plan view of the blank from which the shackle is formed.

Referring now more particularly to the drawing, the device comprises, essentially, a shackle 10 and a locking element 11, the latter including a metal cylinder 12, having extending longitudinally from one end thereof a centrally disposed bore 13, this bore terminating short of the other end of the cylinder whereby a suitable recess will be provided. The cylinder 12 is slotted, as at 14, from the end opposite the entrance to said recess for a distance approximately half its length, said slot being so arranged as to communicate with the recess.

Seated within the recess 13 is a locking spring 15, the same being formed from a length of spring steel, one end of which is

bent upon itself and terminates in an outwardly directed finger 16 which is normally disposed in such position as to intersect the slot 14.

By referring to Fig. 4 it will be noted that the shackle 10 comprises a thin strip of flexible material, one end of which is formed with a tongue or extension 17 and an opening 18 adjacent said tongue. The other end of the shackle is likewise provided with an opening 19 for the purpose to be presently set forth.

In applying the shackle to the cylinder, the tongued end thereof is inserted within the slot 14 with the tongue 17 projecting into the recess 13 and the finger 16 engaging through the opening 18. There is then placed in the recess 13 in any preferred manner, a filling 20 of lead or other suitable substance, said filling serving to close the entrance to the recess and surrounding the ends of the spring 15 and tongue 17 whereby to secure the same in their relative positions.

The device is now in readiness to be employed as a seal, this being accomplished by passing the shackle through the hasp on the article to be sealed and inserting the free end thereof into the slot 14, the finger 16 being compressed by the end of the shackle to permit of the insertion and again springing to its normal position through the opening 19.

It is thus apparent by referring to Figs. 2 and 3 that the ends of the shackle are securely locked within the cylinder 12, opening of the seal being effected only by mutilation of the cylinder or severing the shackle.

What is claimed is:

A car seal comprising a cylinder having a central recess extending from one end thereof and terminating short of its other end, said cylinder being halved longitudinally from the latter end to provide a slot communicating with the recess, a spring seated within the recess, a locking finger at one end of the spring normally intersecting said slot and engaging the closed end of the recess, a shackle having its ends inserted

within the slot with the finger engaged in openings formed therein, a tongue formed at an end of the shackle and passing within said recess beyond the slot, and a plug closing the entrance to said recess and securing the spring and tongue in their relative positions.

Copies of this patent may be obtained for five cents each, by addressing the "Commissioner of Patents, Washington, D. C."

In testimony whereof, I affix my signature, in the presence of two witnesses.

CHARLES F. HRADECKY.
